(57) CLAIM

The ornamental design for a bath brush, as shown and described.

DESCRIPTION

FIG. 1 is a top, front, right perspective view of a bath brush, according to our new design;

FIG. 2 is a bottom, rear, left perspective view thereof;

FIG. 3 is a front view thereof;

FIG. 4 is a right side view thereof;

FIG. 5 is a rear view thereof;

FIG. 6 is a left side view thereof;

FIG. 7 is a top plan view thereof; and,

FIG. 8 is a bottom plan view thereof.

In the drawings, the broken lines illustrate portions of the bath brush that form no part of the claimed design.
